(57) **ABSTRACT**

A new and distinct cultivar of flowering dogwood tree, which produces both fully dark red bracts and lighter red to pink bracts is provided. This dogwood tree is botanically known as *Cornus florida* and referred to by the following cultivar name: 'Erica's Appalachian Sunrise'.

3 Drawing Sheets

Specification includes a Sequence Listing.

1

This invention was made with Government support under Contract No. NACA-58-6062-6 awarded by the U.S. Department of Agriculture. The Government has certain rights in the invention.

The Sequence Listing for this application is labeled "Seq-List.txt" which was created on Oct. 29, 2019 and is 4 KB. The entire content of the sequence listing is incorporated herein by reference in its entirety.

BACKGROUND OF THE INVENTION

The present invention relates to a new and distinct cultivar of flowering dogwood tree with a mixture of both fully dark red and lighter red bracts. This new cultivar was the result of a controlled cross that produced a few seeds, which were planted in a greenhouse in Knoxville, Tenn. This new cultivar was discovered among the resulting seedlings. This dogwood tree is botanically known as *Cornus florida* L. and is hereinafter referred to by the following cultivar name: 'Erica's Appalachian Sunrise'. Analysis has shown that this new dogwood cultivar is the result of self-pollination of the dogwood cultivar 'Cherokee Brave' (U.S. Plant Pat. No. 10,166). The seedling of 'Erica's Appalachian Sunrise' was harvested on its own rootstock. Results have shown that the

2

unique features of this new dogwood cultivar are stable and reproduced true-to-type in successive vegetative generations.

5 BRIEF DESCRIPTION OF THE DRAWINGS

FIG. 1. Photograph of one type of bracts and flowers of the dogwood cultivar 'Erica's Appalachian Sunrise'. This bract has fully dark red coloration and is less than about 5% of the bracts produced by the cultivar. Colors in the photograph may differ from actual colors due to lighting and light reflectance.

FIG. 2. Photograph of 'Erica's Appalachian Sunrise' dogwood cultivar showing the other type of bract and flowers produced more than about 95% of the time on the dogwood tree, which has lighter red or more pink bracts. Colors in the photograph may differ from actual colors due to lighting and light reflectance.

FIG. 3. Photograph of new leaf growth on 'Erica's Appalachian Sunrise'. Colors in the photograph may differ from actual colors due to lighting and light reflectance.

FIG. 4. Photographs of the bracts and flowers of dogwood cultivars 'Cherokee Brave' and 'Karen's Appalachian Blush', (U.S. Plant Pat. No. 13,165), which were initially crossed. Results show that the resulting F1 cultivar, 'Erica's

Appalachian Sunrise', is not, as was expected, related to 'Karen's Appalachian Blush', but is the result of self-pollination of 'Cherokee Brave' (U.S. Plant Pat. No. 10,166). It can be seen that the lighter red or pink bracts of 'Erica's Appalachian Sunrise' (shown in FIG. 2) closely resemble the bracts of the parent, 'Cherokee Brave'.

FIG. 5. Photograph of the less commonly produced bracts and flowers, less than about 5%, of the dogwood cultivar 'Erica's Appalachian Sunrise' (top—fully dark, red bracts), and those of 'Karen's Appalachian Blush' (bottom left) and 'Cherokee Brave' (bottom right).

DETAILED DESCRIPTION OF THE NEW VARIETY

A new and distinct cultivar of flowering dogwood tree producing both fully dark red bracts and lighter red or pink bracts. Both types of bracts are significantly smaller than the bracts of the parent cultivar, 'Cherokee Brave'. This dogwood tree cultivar is botanically known as *Cornus florida* and referred to by the following cultivar name: 'Erica's Appalachian Sunrise'. This cultivar appears to be highly resistant to powdery mildew caused by *Erisiphe pulchra*.

This new and distinct dogwood tree cultivar is a product of self-pollination of the dogwood cultivar 'Cherokee Brave'. The subject dogwood tree cultivar differs from 'Cherokee Brave' in that the instant cultivar produces significantly smaller and both fully dark red bracts and lighter red bracts and also exhibits greater resistance to powdery mildew.

DETAILED BOTANICAL DESCRIPTION

The following observations, measurements and comparisons describe this cultivar grown in Maryville, Tenn. Trees used for this description were about ten (10) years old. Both the fully dark red bracts and lighter red to pink bracts are substantially the same size, though significantly smaller than the bracts produced by the parent cultivar. Plant hardiness is expected to be zones 4-9. The color characteristic descriptions use color references to The Royal Horticultural Society (R.H.S.) Colour Chart, The Royal Horticultural Society, London, UK, 4th Edition, 2001, except where general terms of ordinary dictionary significance are used.

A bee-mediated pollination between the dogwood cultivars 'Cherokee Brave' and 'Karen's Appalachian Blush' was conducted in April of 2009. Seeds were collected from both cultivars and planted in a greenhouse in Knoxville, Tenn. This new and distinct dogwood tree cultivar was discovered among the planting and germination of the seeds harvested from 'Cherokee Brave'. The following Table 1 shows the alleles at nine (9) loci compared between the cultivars 'Karen's Appalachian Blush' (U.S. Plant Pat. No. 13,165), 'Cherokee Brave', and the new cultivar 'Erica's Appalachian Sunrise'. As seen in Table 1, the alleles for 'Erica's Appalachian Sunrise' are identical at all nine (9) loci to those of 'Cherokee Brave' and have no alleles that match 'Karen's Appalachian Blush'. This demonstrates conclusively that dogwood cultivar 'Erica's Appalachian Sunrise' was the result of self-pollination of 'Cherokee Brave'. Asexual reproduction of 'Erica's Appalachian Sunrise' by grafting of axillary buds onto seedling rootstocks has shown that the unique features of this new dogwood cultivar are stable and reproduced true-to-type in successive vegetatively propagated generations.

The cultivar 'Erica's Appalachian Sunrise' has some phenotypic similarities to the cultivar 'Cherokee Brave', but also distinct differences. The following Table 3 provides a comparison of those characteristics for each cultivar that have been observed. Measurements are provided as averages (with ranges also provided as indicated):

TABLE 3

Comparison of Characteristics for Three Dogwood Tree Cultivars		
Character	'Erica's Appalachian Sunrise'	'Cherokee Brave'

Botanical classification: *Cornus florida* 'Erica's Appalachian Sunrise'.

Unique features: A mixture of two types of bracts, a first one being less than about 5% of the bracts produced that is fully dark red and a second type being more than about 95% of the bracts produced that is similar in color to the bracts produced by the parent 'Cherokee Brave'. Both types of bracts on 'Erica's Appalachian Sunset' are similar in size and significantly smaller than the bracts produced by the parent 'Cherokee Brave'. Fewer flowers per inflorescence of 'Erica's Appalachian Sunset' than on 'Cherokee Brave'.

Disease susceptibility: 'Erica's Appalachian Sunrise' has a strong resistance to Powdery mildew caused by *Erisiphe pulchra* and only some spotting caused by *Elsinoe corni*, a cosmetic disease with little damage.

Insect damage: None noted.
